UNITED STATES PATENT OFFICE.

JOHN BIRT MUSE, OF CAMERON, NORTH CAROLINA.

TOBACCO-DRYING APPARATUS.

Application filed January 25, 1924. Serial No. 688,508.

To all whom it may concern:

Be it known that I, JOHN B. MUSE, a citizen of the United States, residing at Cameron, in the county of Moore and State of North Carolina, have invented certain new and useful Improvements in Tobacco-Drying Apparatus, of which the following is a specification, reference being had thereto in the accompanying drawings.

- 10 This invention relates to a tobacco drying apparatus, and the object of the invention is the construction of a comparatively simple and efficient heating apparatus to be placed in a building for drying tobacco.
- 15 Another object of the invention is the improvement of the construction of the fuel-burning part of the apparatus, whereby a very efficient heating of the tobacco-containing building can be accomplished.
- 20 With the foregoing and other objects in view, my invention comprises certain novel combinations, constructions and arrangements of parts as will be hereinafter described, illustrated in the accompanying drawings, and more particularly pointed out in the appended claims.

In the drawings:

Figure 1 is a perspective view of an apparatus constructed in accordance with the present invention, looking at the rear end thereof, while

Figure 2 is a longitudinal, central, sectional view of the same.

Figure 3 is a view, in elevation, of the front of the apparatus.

Figure 4 is a sectional view, taken on line 4—4, Fig. 2, and looking in the direction of the arrows.

Figure 5 is a perspective view of the rear end or back of the apparatus.

Figure 6 is a perspective view of the grate-supporting device.

Figure 7 is a diagram of a building to hold tobacco to be dried, showing my apparatus in position therein.

Figure 8 is a perspective view of a pipe supporting device.

Referring to the drawings by numerals, 1 designates the outer casing and 2 the inner casing of my apparatus. The outer casing 1 rests upon the outer edge 3 of the front end 4 and the back end 5 of the apparatus, whereas both the front and back ends are provided with a shoulder portion 6 (Fig. 5) upon which rests the corrugated inner casing 2 (Fig. 2). The inner casing 2 is cor-

rugated transversely to provide a greater radiating surface which increases the efficiency of my drying apparatus by reason of a greater amount of heat being given off, 60 to pass into the building 7 (Fig. 7).

The front end 4 of the apparatus is provided with a fuel door 8 and a clean-out or ash door 9, Fig. 3.

The rear back end 5 is provided with two 65 openings 10 (Fig. 5) into which extend the tubes or "flues" 11. On each tube 11, near end 5, I place manually operated valve devices 12 (Fig. 7), whereby the amount of heat passing from the furnace into either 70 one of the tubes can be controlled. For instance, if I want all of the heat and smoke to pass through one tube 11, by closing the valve device on the other tube it is obvious that this can be accomplished. Further, if 75 only one part of the building is filled with tobacco, and I desire to have all of the smoke pass through the tube in the filled portion of the building then this can be done by closing the valve device on the tube in the 80 unfilled portion of said building.

I provide a plurality of apertured heat-conveying tubes 13, extending from the upper portion of the end 5 (Figs. 1, 2 and 7). These pipes or tubes 13 can be of varying 85 length, as clearly indicated in Fig. 7, and are detachably mounted at their inner ends in end 5. To suitably support these tubes I provide a pipe supporting device 14 (Fig. 8) which can be stuck into the ground at 90 any desired point, making a easily handled and yet very efficient device for supporting the outer end of a tube 13.

The bottom structure of my apparatus includes grate bars 15 supported at one end 95 upon an angle iron 16, and at their other end (Fig. 2) upon the horizontal flange 17 of the grate supporting device 18. This grate supporting device 18 is cut or formed from a single piece of metal and comprises 100 a horizontal base 19 provided with upstanding sides 20, and an upstanding back 21, which back 21 terminates at its upper edge in a downwardly-extending portion 22. Integral with the lower edge of portion 22 is a 105 horizontal flange 17 upon which one end of the grate rests (Figs. 6 and 8).

I provide a damper device which includes a damper plate 23, and plate 23 is provided with stub shafts 24 that extend through the 110 sides of the inner casing 2 (Fig. 4). An operating rod 25 extends through the front end

4, and this rod is provided with notches 26 for holding it in an adjusted position. The rod 25 is connected at its inner end to a crank arm 27 and the crank arm is fixedly 5 connected to the outer end of one of the stub shafts 24 (Fig. 4), whereby when the operator operates rod 25 the damper plate 23 can be swung forward or backward, as shown by dotted and full lines in Fig. 2, to control the 10 free burning of the fuel on the grate bars 15, whereby the amount of heat derived from my apparatus can be controlled by the operator. For instance, when the damper plate 23 is in the dotted position shown in Fig. 2 15 the fire will be burning freely allowing a quick passage over the damper plate and then into the tubes 11, whereas when the damper plate is in the position shown by full lines in Fig. 2, the free burning will be 20 greatly retarded thereby causing the fire to burn slowly, consequently reducing the amount of heat created for the building 7.

It is to be noted that the position of the damper plate right back of the portion 22 25 acts as an efficient brace or lock for preventing the back 21 from spreading apart, thereby preventing the grate bars 15 from dropping out of place.

I provide a valve plate 28 to cover the 30 vent opening 29, in the side of the outer casing 1.

It is to be understood that the tubes 13 open into the compartment 30 formed between the inner and outer casings, and thereby 35 permit only the heated air to pass into the building 7.

My improved drying apparatus saves one day's time in each curing above the old methods; it saves fifty per cent of the fuel; 40 tobacco is cured out more uniformly, retaining more oil, and more uniform bright color. My apparatus minimizes the possibility of fire, owing to its compact and substantial construction.

While I have described the preferred embodiment of my invention, and have illustrated the same in the accompanying drawings, certain minor changes or alterations 50 may appear to one skilled in the art to which this invention relates, during the extensive manufacture of the same and I, therefore, reserve the right to make such alterations or changes as shall fairly fall within the scope of the appended claims.

What I claim is:

1. In an apparatus of the class described, the combination with an inner and an outer casing, of a grate within said inner casing, supporting means for the forward end of the 60 grate, a support for the rear end of the grate, a damper plate positioned in the inner

casing and having a pivot rod journaled in the side walls of the inner casing, said pivot rod being positioned contiguous to the support for the rear end of said grate 65 and preventing movement of the support out of engagement with the grate, a crank arm between said inner and outer casings and fixedly connected to said damper plate, and an operating rod extending beyond the outer 70 face of said inner and outer casings and positioned also between the same and connected at its inner end to said crank arm.

2. In an apparatus of the character described, the combination of a casing, a grate 75 in said casing, a support for the forward end of said grate carried by said casing, a support for the rear end of said grate positioned in said casing, and a damper plate, and a rod mounting the damper plate in 80 said casing to the rear of the support for the rear end of said grate and serving to retain the support in operative engagement with the grate.

3. In an apparatus of the class described, the combination with a casing, of a grate supporting device provided with a horizontal flange within said casing, a grate supported at one end upon said flange, damper means in said casing, a pivot rod for said 85 damper means positioned in close proximity to the grate supporting device and retaining the same in place with its flange extending beneath said grate, and means in said casing 90 for supporting the other end of said grate.

4. In an apparatus of the class described, the combination with a casing, of a grate supporting device within said casing, said grate supporting device provided with an upstanding back having a grate supporting 100 flange, a damper plate in said casing, a pivot rod for said damper plate to the rear of the upstanding back and preventing rearward movement thereof, a grate resting at one end 105 upon said flange, and means in said casing for supporting the other end of said grate.

5. In an apparatus of the class described, the combination with a casing, of a grate supporting device in said casing, said device provided with an upstanding back provided 110 on one side with a grate supporting flange, a damper device in said casing, a pivot rod for said damper disposed on the other side of said upstanding back from said grate and serving to hold the back in a fixed position, a grate supported at one end upon said flange, and means in said casing for supporting the other end of said grate.

In testimony whereof I hereunto affix my signature.

JOHN BIRT MUSE.
